UNITED STATES PATENT OFFICE

HYMAN MAIMIN, OF NEW YORK, N. Y.

CLOTH-CUTTING MACHINE.

1,170,652.

Specification of Letters Patent. Patented Feb. 8, 1916.

Application filed June 18, 1914. Serial No. 845,822.

To all whom it may concern:

Be it known that I, HYMAN MAIMIN, a citizen of the United States, residing in the borough of Manhattan, city, county, and State of New York, have invented certain new and useful Improvements in Cloth-Cutting Machines; and I do hereby declare the following to be a full, clear, and exact description of the invention, such as will enable others skilled in the art to which it app pertains to make and use the same.

Because of the nature of the service required of cloth cutting machines having rotary cutting blades, it is important not only to protect the rotating parts from the admission of dust thereto, but also to avoid all possibility of the catching up of lint or threads between the rotating blade and any exposed relatively stationary hub or support therefor. For this reason I have devised the herein disclosed novel structure of knife-driving gear, having a ball bearing carried thereby and substantially closed against the admission of dirt and dust, and a supporting stud and knife-clamping cap such that the stud is housed within the gear, while the knife is clamped to the gear, and the relatively stationary stud is at the same time inclosed, by the clamping cap which presents a smooth exterior surface rotating with the knife and having no tendency to catch lint or threads from the cloth.

In the drawings Figure 1 is a side elevation and Fig. 2 is a cross-section of the standard of a cloth cutting machine to which my invention has been applied, and Figs. 3 and 4 are detail views of the knife-driving gear, Fig. 3 being a face view and Fig. 4 a section of the gear on line 4—4 of Fig. 2.

The standard 1 is recessed for the reception of a vertical driving shaft 2, carrying the bevel pinion 3 and the knife-driving gear 4 supported on the standard by the stud 5, and meshing with the pinion 3. The gear 4 consists of a hub plate with a central opening and peripheral gear teeth as shown in Fig. 2, the wall of the central opening being screw threaded to receive the screw threaded hub of the clamping cap 6, which clamps the circular knife 7 against the gear 4 and at the same time closes the central opening of the hub and incloses the end of the supporting stud 5, the result of this arrangement being that the knife, the gear and the cap rotate as a unit and no stationary sup

porting part is exposed at the face of the knife.

There is fixedly carried by the gear 4 a ball bearing comprising the inner and outer raceways 8 and 9, the interposed balls 10 and a spacing ring 11 carrying ball spacing elements 12 (Fig. 4) and substantially closing the ball space on the side facing the wall of the standard. These bearing parts are held in place in the annular recess formed in the gear by turning over the edge of the annular flange 13 as shown at 14 in Fig. 2, and the depth of the hub plate from the central opening to the annular flange 13 is such as to cover the outer raceway 9 and the space between the raceways, but not the inner raceway, as shown in Fig. 2. This arrangement substantially closes the bearing against the admission of dust and dirt and at the same time permits the inner raceway 8 to be clamped against the standard and held stationary by the head of the stud 5.

The entire arrangement is one in which the parts are readily assembled, since it is only necessary to place the stud 5 through the central opening in the inner raceway 8 and screw the stud home until it clamps the raceway, then to place the annular knife against the gear 4 and screw home the clamping cap 6. When so assembled the bearing is well protected against the admission of dust and there are no exposed parts between which there is relative rotation.

Having thus described my invention, what I claim is:

1. In a cloth cutting machine, a standard, a stud projecting therefrom, a knife, a knife-driving gear on the stud and a knife-clamping cap inclosing the end of the stud and coöperating with the gear to clamp the knife between them so that the knife, gear and cap rotate as a unit.

2. In a cloth cutting machine, a standard, a stud projecting therefrom, a knife-driving gear on the stud, and having an internally threaded hub, a circular knife having a central aperture, and a clamping cap having a screw-threaded hub passing through the central aperture of the knife into engagement with the screw threads of the gear so as to clamp the knife between the cap and gear for rotation as a unit.

3. In a cloth cutting machine, an upstanding recessed standard, a vertically disposed knife-driving shaft carrying a bevel gear in

the recess of the standard, a stud projecting laterally from the standard, a coöperative bevel gear mounted for rotation on the stud and having an internally threaded hub, a circular cutting knife having a central aperture, and a clamping cap having a screw threaded hub extending through the aperture of the knife into engagement with the screw threads of the coöperative bevel gear to clamp the knife between the cap and

gear for rotation as a unit, the standard, the cap and the knife forming a closed housing for the gearing.

In testimony whereof I affix my signature, in presence of two witnesses.

HYMAN MAIMIN.
